UNITED STATES PATENT OFFICE.

F. H. MOORE, OF BOSTON, MASSACHUSETTS.

COAL-HOLE COVER.

Specification of Letters Patent No. 12,637, dated April 3, 1855.

To all whom it may concern:

Be it known that I, F. H. MOORE, of Boston, in the county of Suffolk and State of Massachusetts, have invented certain new and useful Improvements in the Covers of Coal-Holes, of which the following is a full, clear, and exact description, reference being had to the annexed drawings, making part of this specification, in which—

10 Figure 1 is a view of the cover with my improvements attached; Fig. 2, a section through the side walk showing the cover closed and fastened; Fig. 3, a similar section with the cover opened.

15 The coal hole covers, as heretofore constructed consists of a simple plate of iron, fitting into an annular plate laid permanently in the side walk immediately over the chimney of the vault. When the hole is 20 opened for the introduction of coal or for other purposes the plate is removed, and when it becomes necessary to ventilate the vault beneath, the plate is partially removed to one side. In either case accidents 25 to passers by are exceedingly liable to occur. To remedy this inconvenience and to produce a cover which may at any time be raised for the purpose of ventilating, or for the introduction of coal or other articles 30 without danger to the passers-by is the object of my present invention, which consists in attaching two or more rods to the underneath surface of the cover, which rods are permitted to slide freely in suitable openings 35 in the cylinder or top plate of the coal hole in a manner which will now be more fully described.

40 A is the cover; b, the rods which are secured thereto, and which slide freely in the tubes B attached to the cylinder C. The rods b are pierced with several holes, through which, and also through holes in the tubes B pass the keys a, by which means the cover may be fastened when closed or

may be secured at various heights above the 45 pavement as required.

In certain cases the holes in the rods and the keys a, may be dispensed with, the cover not being allowed to rise sufficiently to permit the entrance of a man, its motion being 50 arrested by the buttons S at the bottom of the rods.

In Figs. 1 and 3 it is seen raised to its full height for the purpose of introducing coal, and in Fig. 2 it is represented as closed, 55 and bolted by the pins a. The cover may also be raised a few inches for the purpose of ventilation.

In the accompanying drawings the cover is represented as supported by three rods. 60 I do not confine myself however to any particular number of rods as any other suitable number may be employed. In certain cases I propose using but one rod in the center of the plate, the lower end of the rod being 65 screwed and passing through a horizontal bar which is secured across the bottom of the opening. And when the pavement is of flat stone or flagging the cylinder or annular plate above described may be dispensed 70 with, the cover being let directly into the stone, suitable staples being secured to the under surface of the latter to receive the bolts or keys which fasten the cover when closed or elevated. 75

What I claim as my invention and desire to secure by Letters Patent is—

The method of securing the coal hole cover by means of the rods b or their equivalents whereby the cover may be raised more 80 or less as required for purposes of ventilation or for the introduction of coal, and all danger to passers by is avoided as set forth.

F. H. MOORE.
